FLAVEL CREAMER, OF BROOKLYN, NEW YORK, ASSIGNOR TO HIMSELF AND T. W. LADD, OF NEW YORK CITY.

Letters Patent No. 86,060, dated January 19, 1869.

MECHANICAL MOVEMENT.

The Schedule referred to in these Letters Patent and making part of the same.

To all whom it may concern:

Be it known that I, FLAVEL CREAMER, of Brooklyn, in the county of Kings, and State of New York, have invented a new and useful Improvement in Mechanical Movement; and I do hereby declare that the following is a full, clear, and exact description thereof, which will enable others skilled in the art to make and use the same, reference being had to the accompanying drawings, forming part of this specification.

This invention relates to a new and improved arrangement for applying the power of a spring or weight to the propulsion of machinery, it being an addition to the first series of motions of a clock, or similar movement, whereby the objectionable click or noise is avoided, and whereby the power of a spring or weight is more directly applied for propelling light machinery, as for driving sewing-machines, churning, &c.

Figure 1 represents a sectional side elevation of the machine.

Figure 2 is a view of the opposite side, showing the method of imparting motion from a shaft to a rock-shaft and crank-shaft.

Similar letters of reference indicate corresponding parts.

In this example of my invention, I employ the spring and a portion of the movement of an ordinary clock.

My addition and improvement commence with the wheel A, which is placed on and fastened to the shaft B.

The teeth of this wheel are something in the form of ratchet-teeth, as seen in fig. 2.

It is, of course, propelled by the actuating-spring or weight of the movement.

In its revolution it imparts motion to the two pawls C D, alternately, the ends of which pawls are attached, by pivots or joint-pins, to one or more disks e on the shaft f.

These pawls may be curved or bent, as seen in the drawing, and they are guided by the pins i i, which rest and slide on the planes o o.

The pawls are so arranged that the wheel acts upon them alternately. When the wheel comes in contact with the end of one, the other lets go, and the effect is to rock the shaft f.

g is a lever on the shaft f, which partakes of its mo-

tion, and is oscillated vertically thereby, from the outer end of which lever g, a vertical reciprocating motion may be obtained, as indicated in the drawing.

The opposite end of the lever g is connected with a crank on the fly-wheel shaft h.

J is the crank.

K is the fly-wheel.

L is a pulley, from which motion is imparted to revolving machinery.

Rotary motion is given the shaft h by the oscillating lever g, operating on the crank J.

The crank-pin works in a slot, m, in the lever g, so that the lever has no longitudinal motion. The lever-fulcrum is the shaft f.

By this arrangement, either rotary or reciprocating motion is obtained from the spring in a simple and direct manner.

I do not confine myself to any particular arrangement for conveying the power of the spring, or of a weight, to the shaft B, or for regulating the motion.

The advantages of this method are that it works almost noiselessly, thus doing away with the objectionable click of the ordinary escapement-movement, and in obtaining either a rotary or reciprocating movement, as may be desired, in a very easy and direct manner.

It also avoids the friction produced by what is known as the "fly-movement," and it consequently allows the spring to be employed to its utmost capacity for giving strength to this movement.

Having thus described my invention,

I claim as new, and desire to secure by Letters Patent—

The combination and arrangement of the wheel A, propelled by a weight or spring, with pawls C and D, guided by the planes o o, and rocking the shaft f, and communicating motion to the lever g, crank J, and shaft h, all substantially as described.

The above specification of my invention, signed by me, this 27th day of November, 1868.

FLAVEL CREAMER.
